RADIO RECEIVER

Edward F. Andrews, Chicago, Ill.

Application July 18, 1938, Serial No. 219,713

20 Claims.

(Cl. 250—40)

This invention relates to devices for tuning radio receivers in which tuning is effected by power means adapted to be set in operation by manually actuated means and adapted automatically to be rendered inoperative when the receiver has been tuned to the carrier wave of a broadcasting station received with sufficient strength. I call this general type of station selection "stop-on-carrier tuning." The manually actuated means suitably comprises means controlling the change of an electric current or voltage and may be located at a point remote from the receiver. For example, it may be a manually actuated switch which is preferably located in remote relation to the receiver, being connected thereto by means of a cable.

The invention also relates to means for securing the proper timing and for equalizing and narrowing the electrical impulses which cause automatic stoppage on the carrier to effect more exact and uniform tuning.

The invention is very advantageous for tuning all varieties of radio receiver. It facilitates remote control and provides simple automatic tuning which does not require manual adjustments for setting up pre-selected stations.

The invention is very advantageous for effecting automatic tuning for automobile or other portable radio receivers where the receiver may be moved out of the vicinity of certain broadcasting stations and into the vicinity of others. As the form of automatic tuning of this invention will tune in the stations whose carrier waves are of sufficient strength to cause stoppage of the power means driving the tuning element, it is not necessary to re-set the device to tune in a new set of stations when the geographical location of the receiver is changed. The device automatically tunes in the stations broadcasting carrier waves of sufficient strength, regardless of what particular stations they may be, within the tuning range of the receiver.

As tuning from one station to another is effected merely by pressing a button, the tuning operation may be performed by the driver of an automobile without taking his eyes from the road. He may simply continue to operate the tuning button until he hears the desired station. This greatly enhances the safety of radio receiver operation by the driver of an automobile. As only a button or switch connected to the receiver by two small flexible wires is required for performing the tuning operation, this can be very conveniently mounted directly on the steering column, where the driver may operate it

without taking his hand from the wheel, while the receiver may be mounted at any other suitable location in the automobile.

The invention is, of course, also adapted to the automatic tuning of stationary or home types of receiver, and also may be remotely operated in other ways. Also, many of the features described in connection with automobile sets are similarly advantageous for home receivers.

10 The invention will readily be understood from the following description of preferred embodiments thereof, taken in conjunction with the accompanying drawings, in which:

Fig. 1 is a wiring diagram of a radio receiver embodying my invention.

Fig. 2 is a graphical illustration of tuning curves illustrating voltages obtained in certain circuits of the receiver in Fig. 1, shown plotted against frequency.

20 Fig. 3 is a partial wiring diagram illustrating tuning control means adapted to start the rotation of the condensers in either of two directions, and showing a modification of part of the circuit shown in Fig. 1.

25 Fig. 4 is a modification of the arrangement of Fig. 1, in which the motor circuit is opened by the relay spring.

Fig. 5 is a further modification of this invention employing very powerful automatic gain control.

30 Fig. 6 is a partial wiring diagram of an alternating current radio receiver embodying a combination of features of Figs. 1 and 5.

Referring to Fig. 1, the receiver shown is a 35 superheterodyne receiver. Specifically, it represents the Philco superheterodyne receiver built expressly for the 1938 Ford automobile. It will be understood that this receiver is shown by way of example only, since the present invention 40 may be applied to any superheterodyne or to any other radio receiver.

The receiver comprises an antenna 10, a radio frequency amplifying tube 11, which is a No. 78 tube; a first detector and oscillator tube 12, 45 which is a No. 6A7 tube; an intermediate frequency tube 13, which is a No. 78 tube; a diode detector and first audio tube 14, which is a No. 75 tube; a power tube 15, which is a No. 42 tube; a speaker 16; and a "B" power supply, designated by the reference numeral 17, which includes a rectifying tube 18, which may be a No. 84 tube. Energy is supplied to the set from the battery 19, being controlled by a switch 20, which is physically connected to the volume control 21. The set includes transformers and other radio

devices of conventional nature which need no particular description. The set is tuned by a gang 22 of three condensers which serve to tune the antenna circuit, the grid circuit of the first detector 12, and the oscillator circuit. The rotors of the condensers are mounted on a shaft 23 which rigidly carries a gear 24. The gear 24 is driven by a worm 25 mounted on a shaft 26, which may be provided with a knob 27 for manual tuning.

To provide for the mechanical drive of the condensers, I rigidly mount on the shaft 26 a gear 28, which gear meshes with a pinion 29 which is carried by a short shaft 30. The shaft 30 carries projecting clutch elements 31 which are adapted to be engaged by corresponding clutch elements 32 on the shaft 33 of a reversible motor 34. The armature of the motor 34 is biased away from the shaft 30. This may suitably be done by brushes 34* which bear resiliently against the armature. When the motor 34 is energized, the flux moves the armature against the tension of the brushes 34* so that its clutch elements 32 are moved into the path of the clutch elements 31. Immediately the motor is de-energized, the brushes 34* move the clutch elements 32 out of the path of the clutch elements 31 so that the inertia of the armature does not tend to make the condenser overrun. In this way, the tendency of the condenser to overrun is substantially limited to the inertia of the condenser rotor and the drive means connected therewith.

While any type of reversible motor 34 may be employed, in the embodiment shown I employ a direct current reversible motor having two windings 35 and 36, both of which are connected by a lead 37 to the battery lead 38. This connection is located on the side of the switch 28 remote from the battery 19. I prefer to connect a grounded condenser 39 to the lead 37 to attenuate high frequency disturbances. The other ends of the windings 35 and 36 are connected by means of conductors 40 and 41 respectively to a single pole, double throw snap switch 42. This switch is also connected by a conductor 43 to a contact 44 of a relay 45. The snap switch 42 serves to connect the conductor 43 to one or the other of the windings 35 and 36 so as to cause one or the other of these windings to be energized to rotate the motor in one direction or in the opposite direction. The switch 42 is adapted to be thrown in one direction or the other by means of pins 46 and 47. Thus, when the switch 42 is in the position shown in Fig. 1, the winding 35 will be energized so as to cause the motor to drive in the direction corresponding to the arrow shown on the gear 24. When the motor has thereby moved the condensers almost to their extreme position, the pin 46 engages the switch 42 and snaps it so as to connect the conductor 43 to the winding 36. Consequently, the direction of rotation of the motor 34 is reversed and the drive will occur continuously or intermittently, as will hereinafter be more fully explained, until the pin 47 throws the switch 42 back into the position in which it is shown in Fig. 1, again reversing the direction of rotation of the motor. It may here be noted that the movements of the condenser are interrupted when the set is tuned to stations of predetermined strength and are resumed by manual actuation. The movement of the condensers occurs, however, in progressive steps until they arrive at an extreme position, whereupon the direction of rotation of the motor is reversed and the

successive step-by-step movements of the condensers are executed in the opposite direction.

The armature 48 of the relay 45 is adapted to engage the contact 44 and also the contacts 49 and 50 when it is in the position shown in Fig. 1. It is biased to this position by a spring 51. When the relay 45 is energized to a sufficient degree, the armature 48 is withdrawn from the contacts 44, 49, and 50. The armature 48 is grounded and the contact 44 is connected through a resistor 52 and condenser 53 to ground to prevent arcing and sticking at the contact 44.

The winding of the relay 45 is connected to one of the plates 54 of a tube 55, which is a 6F8-G, having two cathodes 56 and 57, a plate 58 which is associated with the cathode 56, a grid 59 which cooperates with the cathode 56, and another grid 60 which cooperates with the cathode 57 and plate 54. This tube is employed as a diode-triode tube, the plate 58 being connected to the cathode 56 which is connected through a condenser 61 to ground. The grid 60 is by-passed through a condenser 62 to ground and is connected through a resistor 63 to the cathode 58. The cathode 58 and the resistor 63 are connected through a resistor 64 to the contact 50. The contact 50 and the resistor 64 are connected through a resistor 65 to a resistor 66, which is connected to the cathode of the tube 15. The cathode of the tube 15 and the resistor 66 are connected to a conductor 67. The other end of the resistor 66, that is, the end which is connected to the resistor 65, is connected to a resistor 68, which is grounded. The cathode 57 is connected to a conductor 69.

The conductors 67 and 69 pass through a cable 70 which may be of any suitable length to provide a suitable location for one or more operating switches 71. These switches are normally closed and they are effective so that when either of them is opened, the motor 34 is started and it continues to operate as long as the switch or switches remain open. When the circuit is closed by removing the finger from the operated switch 71, the motor continues to operate until a station of considerable strength is tuned in, whereupon the motor ceases to operate. It will readily be seen that any number of switches 71 may be provided and they may be located at various positions for operation by the driver or any of the passengers in an automobile, when the invention is incorporated in an automobile receiver. Such switches may be used with receivers in the home, and the cable 70 may be of any desired length so that the radio listener may occupy any position and still have complete control of the tuning of the receiver.

A transformer 72, located between the intermediate frequency tube 13 and the diode detector and first audio tube 14 comprises, the usual windings 73 and 74 in close-coupled relationship, and an additional winding 75 in relatively loose-coupled relation thereto. One end of the winding 75 is connected to the grid 59. The other end of the winding 75 is connected to one end of the winding 74, that is, the end which is remote from the end which is connected to the two diode plates of the tube 14. The winding 75 is tuned by an adjustable fixed condenser 76 to the intermediate frequency.

The resistors 77 and 78 are connected by a conductor 79 to the grids of the tubes 11 and 12 so as to apply a negative voltage thereto to automatically control the volume. Resistors 79' and 80' may be included in the circuits as shown.

The effect of the automatic volume control thus applied to the tubes 11 and 12 has the effect of leveling to a large degree the voltages depicted on Fig. 2, which are derived from signals of varying strength. Thus, the voltages shown in the right-hand part of Fig. 2 may be derived from a signal having a signal strength at the antenna of the order of a hundred times that of the signal from which the voltages shown on the left-hand side of Fig. 2 are derived. Thus, the application of automatic volume control renders the curves 82 very similar and results in a relatively uniform intermediate frequency signal from all received stations, irrespective of very great differences in signal strength. By the use of especially powerful A. G. C., such as will be described with reference to Fig. 5, weak and strong stations may be made to produce signals of substantially similar appearance. However, when this is done, the condenser will stop with equal facility on relatively weak and strong stations alike. Therefore, some difference must be preserved between the signals if it is desired to have the condenser stop only on the stronger carriers. A sensitivity control 116 for adjusting the stop-on-carrier system to stop only at stations of a greater than predetermined signal strength is shown in Fig. 1. Moving the adjustable contact 116' upward causes the condenser to stop on weaker stations, while moving the contact 116' downward causes the condenser to stop only on stations giving a more powerful signal.

The operation is as follows:

When the set is inoperative, the relay 45 is de-energized and the armature 48 is in the position shown in Fig. 1. When the switch 20 is closed, the motor circuit is complete through the conductor 31, one or the other of the windings 35 or 36, the switch 42, conductor 43, contact 44, and armature 48 to ground. Consequently, the condensers are rotated in one direction or the other. At the end of their movement, the direction is reversed, and this condition continues until the tubes warm up to energize the relay 45 with sufficient strength to attract the armature 48 from its initial position. This occurs when the condenser is tuned to a station which will provide a signal of greater strength than a predetermined minimum. If desired, a manually operated or time delay switch 37^a may be included in the conductor 31 to prevent the motor 34 from operating until the filaments have warmed up and current flows in the relay 45. The diode detector elements of the tube 14 will pass current in one direction between the cathode and twin plates of the diode, owing to their connection through the resistances 71 and 78, thus establishing a voltage drop across these resistances. Consequently, the diode detector 14 supplies to the plate 59 a negative bias. This negative bias is shown graphically for two different stations of different strength on Fig. 2, being designated by the reference numeral 79. On the graph shown in Fig. 2, the position of resonance of the intermediate frequency signal with the natural resonance of the circuits containing the windings 73 and 75 is shown on the abscissa at zero.

To provide high fidelity reception from the loud speaker 16, the curve 78, which represents the selectivity characteristics of the intermediate frequency circuits supplying the detector 14, must be fairly broad at the top. The addition of the winding 75 establishes a mutual inductance between this winding and the winding 73. The

result is that the curve 79 tends to have a dual peak, as shown in Fig. 2. The depth of the depression between the dual peaks may be regulated by the degree of coupling between the windings 75 and 73. Closer coupling will accentuate this central depression. The strength of the effective signal is increased thereby, but too close a coupling will cause distortion.

It will be understood, of course, that the negative bias applied to the grid 59 which is used as the plate of the diode element in the tube 55, from the diode detector 14, does not cause current to flow in the circuit containing the diode-cathode 56 and the diode plate 59. In order for such current to flow, it is necessary to apply a positive voltage to the plate 59, which is greater than the negative voltage supplied from the diode 14. This requisite positive voltage is derived from the winding 75 which is loosely coupled to the winding 73, and it is shown graphically on Fig. 2, being designated by the reference numeral 80. Owing to the fact that the winding 75 is part of a low loss circuit, loosely coupled to the windings 73 and 74 and tuned to the intermediate frequency, the curve 80 is quite sharp. It will be understood that the curve 80 corresponds to the selectivity characteristics of the tuned circuit containing the winding 75; therefore, the positive portion of the intermediate frequency signal is impressed on the plate 59 in accordance therewith. This positive voltage is the effective voltage.

In Fig. 2, the curves 82 represent the algebraic sum of the negative and positive voltages indicated by points on the curves 79 and 80, respectively, on the same vertical line. It will thus be seen that the curves 82 represent the voltage effective for causing rectification in the diode section of the tube 55 to impress a positive bias on the grid 60.

Referring to the left hand side of Fig. 2, it will be noticed that up to approximately two kilocycles on each side of the optimum tuning position, that is, the position of the condensers corresponding to zero position on this graph, there is no possibility of current flowing in the rectifier circuit connected to the plate 59 and the cathode 56. The same is substantially true with the case of a much stronger signal, as shown on the right hand side of Fig. 2. The horizontal line 81 on this figure corresponds to the minimum positive voltage necessary to be applied to the plate 59 to cause rectification to occur and sufficient current to pass resulting in a sufficient positive voltage being applied to the grid 60 to cause the armature 44 of the relay 45 to break the motor circuit and stop the rotation of the tuning condenser. It is apparent that this line intersects the two curves 82 at points 83, which are close to the same distance from the optimum tuning position indicated by zero. It will thus be seen that the curves of effective voltage 82 are made of substantially equal width at the base and of fairly similar widths at an operating level indicated by the line 81 by means of this invention. The wide sloping base portion of the curve 80 is cancelled by the similar portion of the curve 79, thus completely eliminating this broad, inexact portion of the signal. It thus becomes possible to approach similar widths of signal by reducing the height of the operating level 81 by increasing the sensitivity of the relay or varying the bias on the grid 60.

It may here be pointed out that the sensitivity control 116 functions in the following manner: When the slider 116' is moved downwardly, the

control grid of the tube 16 is made more negative. As this is a variable mu tube, this results in reducing the mu of the tube or its amplification. This will reduce the height of the curves 19 and 20, and therefore the height of the curve 22 with relation to the operating level line 21. Thus, the signal of certain weak stations will correspond to a curve 22 which is not high enough to reach the operating level line 21. These stations will then not be tuned in by the stop-on-carrier system. If, on the other hand, the slider 16' is raised to a higher level, the weaker stations will produce curves 22 projecting above the operating level line 21 and will then cause the relay 45 to stop the condenser on their carrier waves. Thus, the sensitivity control 16 functions to cause the condenser to stop or fail to stop on the weaker stations, as desired.

It will readily be seen that the endwise moving parts of the motor 34 and the gang of condensers 22 have a certain inertia which causes the condensers to continue to move for a brief interval after the motor circuit is broken. These parts can be readily constructed so that the overrun brings the condenser substantially to the position of optimum tuning; that is, the position corresponding to the zero line in Fig. 2. When the curve 22 is very narrow, it is desirable to construct the condenser drive mechanism, the disengaging clutch 31 and 32, and the rotating parts of the motor 34 so that the condenser will come to a stop as quickly as possible after the opening of the contacts 44. It is also desirable under these circumstances that the relay armature 48 be of small inertia and the relay as a whole be constructed for quick operation.

When the motor is running, that is, when the armature 48 is in the position shown in Fig. 1, the grid 60 is about ground potential. At the same time, the cathode 57 is at a potential higher than ground, owing to the drop across the resistors 66 and 68. When, however, a voltage greater than that corresponding to the line 21 on Fig. 2 is applied to the plate 59, a current flows in the rectifier circuit, including the cathode 56 and the plate 59, which renders the grid 60 positive to a sufficient degree to induce a plate current through the winding of the relay 45 which is sufficient to attract the armature 48 and open the motor circuit. As previously explained, the opening of the motor circuit corresponds to a point such as one of those indicated at 23 on Fig. 2, and the inertia carries the condensers on to a slight extent so that they are located very substantially to the optimum tuned position corresponding to the zero position on Fig. 2.

When the relay 48 moves away from its position shown in Fig. 1, the circuit of the contact 50 is broken, with the result that the grid 60 is made strongly positive, thus ensuring the energization of the relay 45 while that station is tuned in, notwithstanding that the signal of the station may fade below that corresponding to the line 21 on Fig. 2, or even if the station ceases broadcasting entirely.

It will be noted that when the motor 49 is operating, the grid of the power tube 15 is grounded, and consequently the receiver is muted until the relay 45 is again energized to withdraw the armature from the contacts 44, 48 and 50.

When a station is being received, the armature 48 is held by the relay 45. When one or the other of the switches 71 is opened, the ground connection of the cathode 57 is opened, thus in-

terrupting the plate circuit which was energizing the relay 45. Consequently, the spring 51 moves the armature 48 into the position shown in Fig. 1 and the motor operates as long as the switch 71 is held open. After the switch 71 is closed, the motor continues to operate until a carrier of sufficient strength to actuate the relay 45 is again received, whereupon the receiver will receive that station until the set is turned off or one of the switches 71 is opened.

The embodiment of the invention illustrated in Fig. 3 is intended to exemplify an A. C. set in which an alternating current motor 84 is employed. The windings of this motor are connected to a contact 85 of the relay 86, which is comparable to the relay 45 of the embodiment shown in Fig. 1. One pair of windings of the motor 84 are connected to a conductor 87 which is connected to a leaf 88 of a reversing switch 89. The other pair of windings are connected by a conductor 89 to another leaf 91 of the switch 89. Between the leaves 88 and 91 is a leaf 92 which is actuated by the armature 93 of a relay 94. The armature 93 is biased away from the relay 94 by a spring 95 so that the leaf 92 normally makes contact with the leaf 88. The leaf 92 is connected to one end of the secondary of a transformer 96, the other end of which is grounded. The primary of the transformer 96 is supplied by alternating current from the mains, the object of the transformer 96 being to reduce the voltage to suitable proportions for the operation of a small split phase capacitor motor, such as 84. The armature 93 is also rigidly connected to a leaf 97 which is adapted to cooperate with a leaf 98. The leaves 97 and 98 are out of contact when the relay 94 is de-energized, and they are in contact when the same is energized.

The two sets of windings of the motor 84, that is, the sets which are connected to the conductors 87 and 89, respectively, are connected through a capacitor 99. It will readily be understood that when current is supplied to the lead 87, the motor 84 will rotate in one direction, whereas when current is supplied to the lead 89, the motor will rotate in the opposite direction. Consequently, the direction of rotation of the motor depends primarily on the state of energization or de-energization of the relay 94. It may here be noted that in the embodiment of the invention illustrated, the motor 84 tends to rotate the gang of condensers 22 in the clockwise direction or to the right when the relay 94 is de-energized. When this relay is energized, the motor tends to operate to the left or in the counterclockwise direction, as viewed in Fig. 3.

The secondary of the transformer 96 is also connected to the winding of the relay 94 and this winding is also connected to a leaf 100. The leaf 100 is normally in contact with the shorter leaf 101, which is connected by a conductor 102 to the leaf 97. The conductor 102 is also connected to a conductor 103, which may be one of three long conductors which may pass through a cable 104, the other two conductors being designated 105 and 106. The cable 104 may be of any suitable length and it may be provided at its end with a remote control unit designated generally by the reference numeral 107. This remote control unit may comprise any suitable container having two leaves 108 and 109, which are normally biased into engagement with contacts 110 and 111 respectively. The contacts 110 and 111 are connected by a conductor

112. The two leaves 108 and 109 are adapted to be actuated by two buttons 113 and 114 respectively in such a manner that when the buttons are pushed inwardly, the leaves 108 and 109 move away from the contacts 110 and 111, respectively. When the button 113 is thus depressed, it brings the leaf 108 into engagement with a contact 115. Preferably, the contact 110 is somewhat resilient so that it follows the leaf 108 to a limited extent, remaining in engagement therewith until the leaf 108 has engaged the contact 115. The leaf 108 is connected to the conductor 105 and this conductor is preferably grounded at the set. The contact 115 is connected to the conductor 103. The leaf 109 is connected to the conductor 106. The conductor 106 is connected to a resistance 135, the opposite end of which is grounded.

The gang of condensers is indicated by the reference numeral 22, as in the previous embodiment of the invention. The shaft 23 of the gang carries opposite arms 117 which carry pins 118 and 119 which are analogous to the pins 46 and 47 of the embodiment of the invention shown in Fig. 1. It will be noted that when the condenser rotors move in the counterclockwise direction, as viewed in Fig. 3, into one extreme position, the pin 119 engages the long leaf 100 and separates it from the leaf 101, thereby breaking the circuit of the relay 94, allowing the leaves 92 and 97 to attain the position shown in Fig. 3 which has, as will hereinafter be more fully explained, the effect of reversing the direction of rotation of the motor and causing the condenser shaft 23 to turn in the clockwise direction. When the shaft is thus rotated in the clockwise direction nearly to the full movement of the gang of condensers, the pin 118 engages the long leaf 100 and carries the contacting leaf 101 into contact with a leaf 120, which is normally out of engagement with the leaf 101. The leaf 120 is grounded.

The leaf 98 is connected to a contact 121 by a conductor 122. A contact 123 is located adjacent the contacts 85 and 121 so as to be engaged by the armature 124 of the relay 86 when that relay is disengaged. The armature 124 is biased into engagement with these contacts by a spring 125. The armature 124 is grounded. The contact 123 is analogous to the contact 49 of the previously described embodiment and it serves to mute the set when the armature 124 is in engagement with the contacts 85, 121 and 123 during the operation of the motor 84.

In this embodiment of the invention, I provide a diode 126, which may be regarded as one of the diodes of a No. 6H6 tube, and a D. C. amplifying tube 127, which may be a No. 76 tube instead of the diode-triode tube 55 of the embodiment shown in Fig. 1. The elements of the tubes are given the same numbers as in Fig. 1. The plate 59 of the tube 126 is connected to the tuned winding 75, which is loosely coupled to the winding 73. This, together with the closely coupled winding 74, constitutes the transformer 72 between the intermediate frequency tube and diode detector and first audio tube, as in the previously described embodiment.

The conductor 122 is connected through a resistor 128 to the cathode 56 of the tube 126. This cathode is connected to the grid 60 of the tube 127 and is by-passed to ground through a condenser 129. The cathode 51 of the tube 127 is connected through a resistor 130 to a conduc-

70 tor 131, which is connected to the B supply 132 and the winding of the relay 86. The winding of the relay 86 is also connected to the plate 54 of the tube 127. The cathode 51 of the tube 127 is connected to ground through resistors 133, 134, and 135 in series. The conductor 122 is connected by the resistor 136 to the adjacent ends of the resistors 133 and 134. The conductor 106 is connected by a conductor 137 to the common ends of the resistors 134 and 135.

When the set is inoperative, the relay 84 is deenergized and the armature 93 is in the position shown in Fig. 3. The armature 124 is in engagement with the contacts 85, 121 and 123. When energy is supplied to the receiver, which may be done by means of a switch corresponding to the switch 20 in the previously described embodiment, current is supplied from the transformer 86 through the leaf 92 and leaf 98 to the conductor 87, motor coils, contacts 85 and 124 to ground. Consequently, the motor operates to drive the shaft 23 to the right or in the clockwise direction, as viewed in Fig. 3. When the pin 118 is thus brought into engagement with the leaf 100, the leaf 100 and the leaf 101 are brought into conductive relation with the grounded leaf 120. The result is that the armature 93 is attracted and current is now supplied to the conductor 90 of the motor 84, thus causing the motor to operate in the reverse direction; that is, to the left. The leaves 101 and 120 separate immediately this reverse direction begins, but the relay 94 remains energized through the leaves 100 and 101, which are connected to ground through the conductor 102, leaves 97 and 98, conductor 122, contact 121, and armature 124. The movement of the gang of condensers to the left is thus maintained until the pin 119 separates the leaves 100 and 101, thus breaking the circuit of the relay 94 and allowing the armature 93 to attain the position shown in Fig. 3, which adapts the device for condenser operation in the clockwise direction. Consequently, the tuning device moves from one extreme position to the other until the tubes are heated up sufficiently to bring in a station with sufficient strength to stop the motor, in substantially the same manner as described in connection with the embodiment of Fig. 1.

55 As in the previously described embodiment, no current flows between the plate 59 and the cathode 56 until the plate 59 becomes positive relative to the cathode 56. When plate current flows through the resistor 128 to ground through the contact 121 and armature 124, a certain positive potential is applied to the grid 60 so that it may become more positive. When a signal which gives a curve 82 (Fig. 2), which is greater than the voltage corresponding to the line 81, is received, sufficient current flows through the relay 86 to energize it and the armature 124 is withdrawn from the contacts 123, 121, and 85, and the motor circuit is broken. When the armature 124 moves away from the contact 121, B voltage is applied through resistor 130, resistor 133, resistor 136, and resistor 128 to the grid 60, so that a still larger current flows through the relay 86, maintaining this relay energized indefinitely even if the received signal fades or ceases. The resistor 135 is preferably quite large in comparison to the resistors 133 and 134, but is quite small compared with the resistor 130. The resistor 135 is not normally in the circuit of the cathode 51, since the resistor 134 is grounded through con-

ductors 137, 106, 112, and 105. This ground circuit is interrupted when either of the two buttons 113 and 114 is pressed, with the result that the relatively large resistor 135 is introduced into the plate circuit, reducing the current through the relay 86 to such an extent that the armature 124 is released. It will be noted that the switches 71 in the previously described embodiment open the plate circuit. In the present embodiment, the introduction of the high resistance 135 into the plate circuit is distinctly analogous and has the same effect.

When the button 114 is pressed inwardly, it merely has the effect of introducing the resistor 135 into the plate circuit of the tube 127. Consequently, the motor will operate towards the right, and if the button 114 is held inwardly, the rotor of the condenser 22 will be driven to the right, until at last the pin 118 comes in contact with the leaf 108 and starts the motor to the left in the manner previously described; that is, through the energization of the relay 94. When this relay is energized, the button 114, being still pressed inwardly, it is locked in energized relation through leaves 100, 101, conductor 102, leaves 97 and 98, conductor 122, contact 121, and armature 124. If the button 114 is still maintained pressed, the pin 119 breaks the circuit of the relay 94 and movement of the condenser to the right is again resumed. If, at any point of the cycle thus described, the button 114 had been released, the motor would continue to tune the set until an arresting carrier was tuned in. This arresting carrier would result in energization of the relay 86, the stopping of the motor 84, and the de-energization of the relay 84, if it were in a state of energization.

As has previously been remarked, the contact 110 preferably follows the leaf 108 when the button 113 is pressed inwardly until the leaf 108 has engaged the contact 115. When the button 113 is pressed inwardly, the relay 94 is energized, the circuit being as follows: secondary of transformer 96, relay 84, conductor 102, conductor 103, contact 116, leaf 108, and conductor 105. Consequently, the motor is brought into operation to drive the gang of condensers 22 to the left, and this movement is continued as long as the button 113 is pressed inwardly. If it is maintained pressed inwardly until the pin 119 moves the leaf 108 away from the leaf 101, the relay 94 will be de-energized and the motor 84 will start to the right until the leaves 100 and 101 are again brought into contact. Thus, any chance of injury to the motor is prevented by providing for the reversal of the motor at both ends of the throw of the gang of condensers.

It will be understood, of course, that if the button 113 is pressed inwardly and then released, the gang of condensers 22 will start moving to the left and the motor 84 will be arrested when a carrier wave of sufficient strength is brought in.

It will be understood that the contact 110 may be stationary so that the motor can be started to the right by depressing the button 113 sufficiently to disengage the pole 108 from the contact 110. If the button 113 is further depressed so as to bring the leaf 108 into engagement with the contact 116, the motor will start to the left. Consequently, I may have one button 113 or a plurality of similar buttons arranged in parallel, each of which can start the motor to the right or the left, as desired. In this case, the button

114 may be omitted, the conductor 112 being connected directly to the conductor 106.

In the embodiment of the invention shown in Fig. 4, the reference numeral 138 indicates the last intermediate frequency tube, the plate of which is connected to the primary 139 of a transformer 140, which is analogous to the transformer 12 of the previously described embodiments of the invention. The secondary 141 of this transformer, which is closely coupled to the primary 139, is connected to the diode plate 142 and through resistors 143 and 144 to the cathode 145, which is located in the tube 146 with the diode plate 142. The tube 146 also includes the triode elements, that is, the grid 147 and the plate 148. The grid 147 is connected to the adjacent ends of the resistors 143 and 144. The secondary winding 141 and the resistor 143 are connected through a resistor 149, condenser 150, and a volume control 151 to the grid of the first audio frequency tube 152. The rectifier plate 148 of the tube 146 is connected to one end of a winding 153, which is loosely coupled to the transformer 140, being analogous to the winding 15 of the previously described embodiments. The winding 153 is tuned to the intermediate frequency by the condenser 154. The end of the winding 153 remote from its connection to the plate is connected through a resistor 155 to ground and is also connected to the grid 156 of the tube 157. The cathode 158 of the tube 157 is connected through resistors 159 and 160 to ground. The common ends of the resistors 159 and 160 are connected by the conductor 161 to a contact 162. A plate 163 of the tube 157 is connected through the relay 168 to the B supply 169. The end of the winding of the relay remote from its connection to the B supply 169 is connected through a resistor 170 to a pole 171 of the normally open switch 172. When the pole 171 is manually depressed, the resistor 170 is grounded. A contact 173, which is located adjacent the contact 162, is connected by a conductor 174 to the grid circuit of the audio frequency tube, not shown. A contact 175, which is located in alignment with the contacts 162 and 173, is connected by a conductor 176 to the motor (not shown). When the relay 168 is energized, the armature 177 is moved into engagement with the contacts 162, 173 and 175, thereby muting the receiver, driving the motor, and increasing the energization of the relay 168. It will thus be seen that this relay 168 is quite analogous to the relay 45 of the first described embodiment, but it operates in the opposite direction.

When the button 171 is depressed, the motor starts operating, and when a carrier of sufficient strength is received, the flux of the relay 168 decreases and the armature 177 is moved away from it by a spring 178. The removal of the armature 177 from the contact 162 decreases still further the flux of the relay 168, thus providing a locking effect. This locking effect can, however, be obtained in other ways; for example, the armature 177 may be arrested by a stop 177' sufficiently far away from the relay 168 so that the current necessary to energize the relay 168 so as to move the armature 177 towards the relay, is much greater than the current strength at which the relay 168 releases the armature 177 under the action of the spring 178. The operation is as follows:

When energy is supplied to the set, the condenser remains inoperative until the tubes warm

up. If the condenser is tuned for the reception of a station of sufficient strength, that station will be received. If the switch 171 is closed, B current flows through the relay coil 168 and resistor 170, and the grounded relay armature 171 will be brought into engagement with the contacts 162, 173 and 175, and the motor will operate as long as the contact is depressed. It will be understood that the motor may be reversed in the manner described in connection with Fig. 1. If the switch 171 is opened after being pressed momentarily or for a longer period, the motor continues to operate until a carrier wave of sufficient strength is received, which carrier wave has the effect of decreasing the plate current of the tube 157, so that the spring 178 opens this relay and terminates the operation of the motor.

It will be understood that the cathode 145 and the plate 142 constitute the second detector of the receiver. This diode circuit creates a voltage drop across the resistors 143 and 144, with the result that the grid 147 is more negative than the cathode 145. The signal strength is proportional to the drop of potential across the resistor 144, so that the stronger the signal, the greater is the negative voltage applied to the grid 147 relative to the voltage of the cathode 145. Thus, the stronger the signal, the greater is the tendency for the grid 147 to oppose the passage of plate current between the plate 148 and the cathode 145. The negative voltage applied to the grid 147 varies in the general manner shown by the curve 79 on Fig. 2, it being understood, however, that the curve 79 involves the amplification factor of the triode elements 145, 147 and 148, which constitute a grid controlled rectifier. The positive component of the loosely coupled winding 153 is applied to the plate 148 and has a characteristic corresponding to the curve 80 of Fig. 2. Consequently, the plate current, corresponding in magnitude to the curve 82 of Fig. 2, will flow between the plate 148 and the cathode 145 when a station of sufficient magnitude is brought in. This plate current passing through the resistor 155 lowers the voltage of the grid 156 so that the plate current of the tube 157 is reduced sufficiently to effect the withdrawal of the armature 171 from the contacts 162, 173 and 175 under the action of the spring 178. It will be understood that the station thus received may fade or sign off without the relay 168 being energized sufficiently to again attract the armature 171. The reason for this is that the contact 162 is no longer grounded and has the effect of increasing the positive bias of the cathode 158, thereby decreasing the current flowing through the relay 168, and furthermore, the armature 171 is removed from the position of strongest flux of the relay 168.

In the previously described embodiments, a certain negative automatic gain control or A. G. C. voltage is applied to the grids of certain of the earlier tubes of the receiver for the purpose of varying their gain or amplification to secure automatic gain or volume control. Since the resulting reduction of the gain on stronger signals reduces the A. G. C. voltage, the various received signals, while rendered very much more uniform in strength, still show considerable differences after amplification between the signals produced by a weak and a strong station. This is exemplified in Fig. 2, where the strength of the signal illustrated on the right is approximately double the strength of the signal illustrated on the curves of the left of this figure.

I have discovered that I can attain much greater uniformity of signal for stop-on-carrier tuning by applying the negative A. G. C. voltage to the grid of a radio frequency or intermediate frequency amplifier not located in front of the circuit in the amplifier supplying energy to the A. G. C. rectifier. In other words, a more powerful A. G. C. effect can be obtained from a tube which does not contribute to the amplification of the signal operating the A. G. C. rectifier. This is true because the reduction of amplification of this tube does not reduce the A. G. C. voltage as is the case when the tube precedes the A. G. C. rectifier. I call this form of automatic gain control "after A. G. C." to differentiate it from the ordinary A. G. C. applied to a tube which is before the A. G. C. rectifier and through which the signal operating the A. G. C. rectifier must pass. By employing both "before" and "after" automatic volume control, I may obtain control voltages for stop-on-carrier which are very close to uniformity for all received stations. By operating in this manner, I produce a stop-on-carrier receiver such as that illustrated in Fig. 5, which may cause all the signals, both weak and strong, which will affect the stop-on-carrier system, to operate very much alike.

Referring to Fig. 5, the reference numeral 179 designates the last intermediate frequency tube, which is coupled by a transformer 180 to the second detector and first audio frequency tube 181. The detector circuit of the tube 181 includes resistors 182 and 183 from which are derived negative voltages which are applied by conductors 184 to the grids of certain of the earlier tubes in the receiver. A conductor 185 is connected to the two resistors 182 and 183 and to a coil 186 which consists of a few turns tightly coupled to the primary of the transformer 180. The coil 186 is connected to the grid of an intermediate frequency amplifying tube 187, which is outside the radio receiver circuit. That is, the tube 187 and the tube 188 to which it is connected through the transformer 189, have no part in the conveyance or amplification of the audible signal. The transformer 189 is loosely coupled and its windings are sharply tuned to the intermediate frequency, which has the effect of narrowing the resonance curve for the signal passing through the tube 187. Consequently, the tube 188 will only draw substantial plate current when the intermediate frequency signal is near the resonant frequency of the transformer 189. Furthermore, on account of the "before" and "after" A. V. C., the maximum value of the signal of the tube 188 is substantially the same for all effective stations. The current delivered by the tube 188 passes through a relay 190, which controls the motor circuit 191.

The relay 190 is biased open by a spring 192, and when the relay 190 is opened, its armature 193 makes contact with the motor circuit 191. It may here be noted that the motor circuit may be completed as in the modification of Fig. 1. When the motor circuit is closed, an armature 193, which is grounded, engages a contact 194 which is connected by a conductor 195 to the grid circuit of the second audio tube, not shown. Consequently, when the motor is operating, the set is mute. When the armature 193 is in engagement with the motor circuit 191 and the contact 194, it opens a switch 196. This switch is arranged to close when the relay 190 is energized. One side of the switch 196 is connected through a resistor 197 to the plate of the tube 188 and to

one end of the winding of the relay 190. The other end of the winding of the relay 190 is connected to the B supply. The cathode of the tube 188 is connected through a resistor 198 to the other side of the switch 196. The common point between these elements is grounded through a normally closed switch 199.

The operation is as follows: When energy is supplied to the set, the motor circuit being closed, the motor runs in the manner described with respect to the embodiment of Fig. 1, unless a delayed switch 37^a is provided. It will be understood that the gang of condensers reverses automatically, as in the embodiment illustrated in Fig. 1. The audible signal passes through the tubes 179 and 181 and through the triode plate of the latter tube to other audio frequency tubes and to the speaker. The automatic volume control applied by the conductors 184 to the earlier tubes of the receiving set has the effect of reducing very greatly the difference of strength of signal reaching the tube 181. The "after" A. G. C. voltage applied by the conductor 185 to the tube 187 may be adjusted to render substantially equal signals appearing in the tube 188 from all stations above a certain signal strength. Substantial equality may be obtained by properly proportioning the resistors 182 and 183 to impress the desired portion of the voltage drop across these resistors on the grid of the tube 187. These resistors may also be proportioned so as to get any desired ratio less than equality between the signals produced by the strongest and the weakest stations to be received. It is even possible to make the signal of a strong station produce a smaller signal in the tube 188 than would be produced by a weaker station. It is generally desirable to approach equality between weak and strong stations for the purpose of very exact tuning. In addition to the equalizing effect of the after A. G. C., the loose coupling and sharp resonance of the primary and secondary circuits of the transformer 189 may be adjusted to make the stop-on-carrier signal highly selective; that is, to narrow the width of the motor stopping signal in terms of degrees of condenser rotation.

It will be understood that when the plate current of the tube 188 is sufficient; that is, when the intermediate frequency produced by a station of sufficient signal strength closely approaches the adjusted frequency of the transformer 189, the armature 193 is moved away from the motor contact and from the contact 194, so that the motor stops and the station may be audibly received. When the relay 190 is energized, the plate current flows from the B supply through the winding of the relay 190, the tube 188, the resistor 198, and the switch 199. The relay 190 is energized during the reception of a station. The switch 196 is then closed and a parallel circuit is completed from the B supply through the winding of the relay 190, the resistor 197, the switch 196, and the switch 199. Consequently, when the switch 199 is opened, both of these circuits are interrupted and the relay 190 is de-energized so that the motor tunes in another station. It will be understood that the additional circuit just referred to has the effect of locking the relay 190 during the reception of a station until the switch 199 is opened manually.

The embodiment of the invention illustrated in Fig. 6 comprises a radio frequency tube 260, an oscillator and first detector tube 261, a first intermediate frequency tube 262, a combined diode 263 and second intermediate frequency elements 75 264

264 enclosed in a single tube 265, a double diode 266, which may be a No. 6H6 tube, a first audio frequency tube 267, which is connected to other audio frequency tubes or the loud speaker, and a gas tube 268, which may be a No. 884 tube. The last named tube may be considered as being out of the set since it is merely used for the control of the relay 269. The set is tuned by a motor 270 which controls the position of three condensers 271, 272 and 273, which may be arranged in a gang, as in the first described embodiment of the invention. The condensers control a switch 274, which is analogous to the switch 42 of Fig. 1, and which is actuated at extreme positions of the condenser to reverse the motor, thereby reversing the direction of movement of the condenser. The motor 270 is supplied with current from power lines through a transformer 275. When the relay 269 is de-energized, the armature 276 is retracted by a spring 277 so as to ground a conductor 278 which is connected to the motor 270 through the switch 274 and a conductor 279, which has the effect of muting the set in the manner described with reference to the previously described embodiments. When the relay 269 is energized, the armature 276 is attracted and breaks the motor and muting circuits.

The plate of the diode 263 is connected through a winding 280, which is grounded through resistors 281 and 282, which provides a negative A. V. C. voltage. This voltage or part thereof is applied in the "before" or "after" A. V. C. previously described. Thus, the maximum negative voltage is applied through a resistor 283 to the grid of the tube 260. A lesser degree of negative voltage which corresponds to the voltage drop across the resistor 282 is applied through resistor 284 to the grids of tubes 261 and 262. A still lesser amount of the negative voltage, being that corresponding to a part of the voltage drop across the resistor 282, is applied to the grid of the intermediate frequency tube elements 264, this being the position at which the "after" A. V. C. is applied. The winding 280 consists of a few turns closely coupled to the primary of a transformer 285, which connects the plate circuit of the tube 262 to the grid of the intermediate frequency amplifying elements 264 in the tube 265.

For the reasons set forth above, the "before" and "after" A. V. C. gives a signal in the plate circuit of the intermediate frequency elements 264 which can be made substantially equal for all received stations, strong or weak. This signal passes through the primary of a closely coupled transformer 286, the secondary of which is located in the plate circuit of one of the diodes 288 in the tube 266, this secondary being in series with a resistor 287. The diode 288 serves as the detector for the set, and the negative side of the resistor 287 is connected through a resistor 289, condenser 290, and volume control 291 to the grid of the first audio tube 261. The negative or plate side of the resistor 287 is also connected through a winding 292 to the plate of the diode 293 in the tube 266. The cathode of the diode 293 is grounded through a resistor 294. The positive side of the resistor 287 is also grounded. The cathode of the diode 293 is also by-passed through a condenser 295 to ground. This cathode is also connected through a resistor 296 to the grid of the gas tube 268. The grid of this gas tube is also by-passed to ground through a condenser 297.

The plate of the gas tube 268 is connected through the winding of the relay 269 to the B supply. The B supply is connected through a high resistance 288 to the cathode of the tube 268. The cathode of the tube 268 is connected through a resistor 299 to the normally closed manually actuated switch 300, the other side of which is grounded.

It will readily be understood that the plate of the diode 283 is subjected to a negative voltage derived from the voltage drop across the resistor 287, which voltage drop corresponds to one of the curves 18 in Fig. 2. The plate of the diode 293 also receives an intermediate frequency signal, the positive phase of which corresponds to one of the curves 80 in Fig. 2. Consequently, the positive phase of the voltage across the coil 292 impressed upon the plate of the diode 293 is indicated by one of the curves 82 on Fig. 2. It may here be noted that the effect of the "before" and "after" A. V. C. is to render the two sets of curves shown in Fig. 2 and the corresponding curves for both strong and weak stations very much more uniform. The further result is that all of the curves 82 for received stations can be made practically uniform, both as to height and breadth. As previously described, it is also possible by applying various portions of the voltage drop across the resistors 281 and 282 as "after" A. V. C. to establish any desired ratio of signal between the strongest and weakest signals effective on the grid of the tube 268 to be received. For instance, the effective signal of the strongest station to be received might cause a voltage change only twice as great as the weakest signal to be received, although the corresponding signals, as received on the antenna of the set, may have a tremendously greater difference.

When a station is being received, current flows in the gas tube 268, the relay 269 is energized, the motor circuit is broken, and the mute circuit is open. When the switch 300 is opened, the plate circuit of the tube 268 is broken and the armature 276 is released. Consequently, the motor operates until the switch 300 is allowed to close again. After the switch 300 closes (and it may here be noted that it may be opened momentarily only), the motor continues to operate until a carrier wave of adequate strength is received, whereupon rectified current flows through the resistor 294, thereby making the cathode end of the resistor 294 positive. This positive voltage is communicated through the resistor 296 to the grid of the tube 268. The resistor 296 and condenser 297 serve as time filter circuits which prevent the tube 268 from responding to static or other undesired electrical disturbances of extremely brief duration. It will be noted that the grid of the tube 268 does not need to become positive with respect to the cathode of this tube in order to start the current through the relay 269. It merely needs to have its negative bias reduced below a certain point determined by the characteristics of the tube, the plate voltage applied, etc. This reduction of negative voltage on the grid of the tube 268 is attained when a received carrier gives a signal corresponding to the curve 82 (Fig. 2) of magnitude greater than a certain value, for example, that corresponding to the line 81 on this figure.

As has been previously described, the opening of the switch 300 breaks the plate circuit of the tube 268, resulting in starting the motor 276. After the switch 300 is allowed to close, the mo-

tor continues to operate until the next station of sufficient strength is tuned in.

It will be understood that the tube 268 passes its full plate current as soon as the negative voltage of its grid falls below the value which prevents ionization. In other words, the grid acts as a trigger controlling the plate current, but once ionization is established and plate current flows, the plate circuit must be interrupted, the plate voltage reduced below the ionization point, or the negative bias on the grid enormously increased to stop the flow of plate current. This quality of the gas tube therefore provides similar locking characteristics to those obtained in the other embodiments by special locking circuits. The action of the gas tube 268 is very rapid. Its time characteristics, however, can be controlled by means of the time constant of the filter circuit composed of the resistor 296 and condenser 297. Increasing the resistance of the resistors and the capacity of the condensers increases the time interval, and vice versa. The time filter circuit connected to the grid of the tube 268 should be so proportioned that the action of the tube 268 is as rapid as possible, but still slow enough so as to require a signal of appreciable duration to cause it to ionize. In other words, it should work as rapidly as possible on a continuous carrier wave, but should not respond to static or other undesired disturbances of negligible duration.

There are certain considerations pertaining to the time interval between the instant at which the signal is tuned closely enough to resonance to effect the interruption of the motor circuit and the instant that the condenser comes to a full stop, which should be considered for proper operation of this invention. Lag or delay tending to prolong this interval can occur in several ways. First, the filters employed in connection with rectifiers contributing to the stop-on-carrier signal must not have too long a time constant if the quickest possible stoppage is desired. Of course, the characteristics of the whole system must be considered. If a sharp selective stop-on-carrier signal is employed, then the distance or time available between the effective stop-on-carrier signal and arrival at the peak of the carrier wave is very short and the time constants of all portions of the system must be made very small to prevent passing the peak of the carrier before complete condenser stoppage occurs. On the other hand, if the stop-on-carrier signal is relatively broad, then too quick action will result in condenser stoppage before the peak of the carrier is reached. Accuracy and uniformity of tuning are, however, facilitated by sharp tuning of the carrier signal and corresponding reduction in the time lag all along the line. This procedure in connection with the equalization of the effective width of strong and weak signals is the preferred arrangement.

When the time constants of the rectifiers are sufficiently short, the next point of delay to be considered is the stop-on-carrier relay. The operation of the relay may be accelerated by reducing the inertia of the moving parts, by reducing hysteresis and eddy current effects, and by supplying a large sudden increase of plate current to provide a powerful relay action. It is also generally desirable to close the magnetic circuit of the relay for quickest action rather than to open it. This means that fast action is obtained when energization of the relay stops the motor. It will be understood that it is desirable also to reduce

the weight and inertia of the parts rotating with the rotor of the condenser. A considerable inertia, however, is unavoidable in the armature or rotor of the motor employed in driving the condenser. It is therefore preferable to provide means whereby the condenser or other variable reactance can be brought to a full stop while the armature of the motor is still rotating. If a clutch is provided for this purpose, as shown in Fig. 1, it is desirable to reduce as far as possible the time required for the clutch to release. Other means of eliminating the effect of the motor armature inertia may also be employed, such as a friction drive between the motor and the condenser with provision for abruptly stopping the condenser, while the armature may continue to rotate for a short interval by slippage of the friction drive.

It will be further understood that the importance of eliminating the stopping lag increases with the speed at which the motor turns the condenser. If this speed is quite slow, requiring for instance, ten or twenty seconds for a half revolution of the condenser rotor, the time lag may not need to be especially reduced. It might even be necessary to increase it. But it is desirable to drive the condenser at relatively high speed so that only a brief interval is required to tune from one station to the next. This facilitates selecting the desired station by tuning from one station to the next in the shortest period of time. It is thought desirable for this purpose to turn the condenser one-half revolution in from two to not over five seconds, and it is desirable to work closer to the lower figure.

To achieve the most rapid operation with exact and uniform tuning, it is desirable that a given number of degrees of condenser rotation should result in changing the tuning by a given number of kilocycles alike from the high to the low frequency ends of the tuning range. For this purpose, a condenser having a substantially straight line frequency characteristic, at least to within a short distance of the low frequency end, may be employed. To keep the straight line frequency characteristic all the way to the low frequency end might involve too great a structural disadvantage in the condenser, although it is desirable otherwise. A variable inductance may also be employed for tuning, for instance, one in which the inductance is changed by varying the permeability or reluctance. In this case, a uniform change of frequency with rotation is of similar advantage. With slower tuning, this straight line frequency characteristic is of lesser importance.

Although the invention has been described in connection with the specific details of preferred embodiments thereof, it must be understood that such details are not intended to be limitative of the invention except insofar as set forth in the accompanying claims.

Having thus described my invention, I declare that what I intend to claim is:

1. In combination with a radio receiver having a power actuated tuning element, a grid controlled gas tube having a cathode and plate, means for supplying a steady direct current voltage to the plate of the gas tube, fast acting direct current means in the plate circuit of said tube actuated by a change in the direct plate current of said gas tube to stop the movement of said tuning element substantially at resonance, rectifying means and means for impress-

ing a voltage from said rectifier on the grid of said gas tube to stop said tuning element.

2. In combination with a radio device having an adjustable control, electric power means for driving said control in both directions, a source of electric current therefor, relay means for stopping and starting said power means, a second relay means for reversing said power means biased to normally operate said power means in one direction, switch means for energizing said stop and start relay means, switch means for energizing said reversing relay means, and means for manually operating one switch means to start in one direction and both said switch means to start in the other direction.

3. In combination with a radio receiver, a tuning element, means actuated by a change in the plate current of a grid controlled electron tube to stop the movement of said tuning element substantially at resonance, electric power means for driving said tuning element, a source of electric current therefor, relay means for stopping and starting said power means, a second relay means for reversing said power means biased to normally operate said power means in one direction, switch means for energizing said stop and start relay means, switch means for energizing said reversing relay means, and means for manually operating one switch means to start in one direction and both said switch means to start in the other direction.

4. In combination, in a superheterodyne radio receiver having an intermediate frequency section and a second detector, a shielding container, second detector coupling means within said container, a power actuated tuning element, a grid-controlled electron tube, means actuated by a change in the plate current of said electron tube to stop said tuning element when the intermediate frequency signal is in substantial resonance with said intermediate frequency section, means including a pair of circuits tuned to the intermediate frequency housed within said container and having mutual coupling adapted to produce a first control voltage having a selectivity curve with two peaks and a depression therebetween, means for deriving from said receiver a second control voltage having a single peak coinciding with said depression and exceeding said first control voltage when a carrier signal is closely tuned in, and means including rectifying means for applying a voltage depending upon the difference between said first and second control voltages to said electron tube adapted to produce a change in the plate current of the electron tube.

5. In a radio receiver, in combination, a variable tuning element, a motor for operating said tuning element, a clutch connecting said motor to said tuning element, an ionizing gas tube having a grid and plate, electrical means in the plate circuit of said gas tube for controlling said clutch, tuned coupling means deriving from said receiver a first control voltage having a selectivity curve with two peaks and a depression therebetween, tuned coupling means deriving from said receiver a second control voltage having a selectivity curve with a single peak coinciding in frequency with said depression and exceeding first said control voltage when a carrier signal is closely tuned in, means including rectifying means for applying a voltage depending upon the difference between said first and second control voltages to said grid to ionize said tube when a carrier signal is closely tuned, there-

by to cause said electrical means to disengage said clutch and stop said tuning means closely on said carrier signal.

6. In a radio receiver having a variable tuning element, in combination, power means for driving said tuning element, relay means controlling said power means and tuning element, said relay means being operable when deenergized to render said power means effective to drive the tuning element and when energized to stop said power means and tuning element, an ionizable gas tube having an output circuit connected to said relay means and a control grid, means connected to said grid to supply it with a control voltage from the receiver for ionizing said tube and energizing said relay when a carrier signal is closely tuned in, a source of direct current connected to said plate circuit for maintaining said tube ionized and said relay means energized, and normally closed switch means in said plate circuit operable to open said plate circuit for deionizing said gas tube and deenergizing said relay means.

7. In a superheterodyne receiver having variable tuning means, in combination, a motor for actuating said tuning means, switch means controllable by an operator for starting said motor, an intermediate frequency transformer having a primary winding tuned to intermediate frequency, a tuned circuit coupled to the primary of said intermediate frequency transformer, said circuit being tuned to intermediate frequency and having a degree of mutual coupling to the primary of said transformer such that the selectivity curve of the primary has two peaks with a depression therebetween and the selectivity curve of said tuned circuit has a single peak coinciding in frequency with said depression and the voltage of said tuned circuit exceeding that of said primary only when a carrier signal is closely tuned in, a rectifier having a plate and a cathode, one terminal of said tuned circuit being connected to supply said plate with an intermediate frequency voltage, other rectifying means energized from the primary of the intermediate frequency transformer and delivering a negative rectified voltage to said plate, a tube having a grid and plate with its grid connected to said cathode, and a relay operated by the plate current of said last tube for stopping the motor and movement of said tuning means when the positive phase of the intermediate frequency voltage exceeds the negative voltage by a definite amount.

8. In a radio receiver having a variable tuning element, in combination, power means for driving said tuning element, relay means adapted when energized to stop said power means and tuning element, an ionizable gas tube having a plate circuit connected to said relay means and a control grid, means connected to said grid to supply it with a control voltage from the receiver for ionizing said gas tube and energizing said relay means when a carrier signal is closely tuned in, a source of direct current connected to the plate circuit of said tube for maintaining said tube ionized and said relay means energized, and a time delay circuit connected between said grid and control voltage source having a time constant short as compared to the time of operation of said relay and long as compared to the duration of static impulses.

9. In a radio receiver having variable tuning means, in combination, electrically actuated means for stopping and starting said tuning means, an electron tube having a plate circuit

connected to said electrically actuated means and a grid controlling the plate current for operating said electrically actuated means, means including a pair of circuits tuned to the same frequency associated with said receiver and having a mutual coupling adapted to produce a first control voltage having a selectivity curve with two peaks and a depression therebetween, means for deriving from said receiver a second control voltage having a single peak coinciding with said depression and exceeding said first control voltage when a carrier signal is closely tuned in, means including rectifying means for applying a voltage depending upon the difference between said first and second control voltages to said grid when said carrier signal is closely tuned to operate said electrically actuated means and stop said tuning means closely on said carrier signal, and means actuatable by an operator to operate said electrically actuated means to restart said tuning means.

10. In a radio receiver having power actuated tuning means, in combination, a transformer having a tuned primary circuit and a tuned secondary circuit coupled thereto to cause the voltage selectivity curve of said primary to have two peaks and to cause the voltage selectivity curve of said secondary to have a single sharp peak located with respect to frequency at the depression between the two peaks of the primary selectivity curve and exceeding the voltage of the double peaked selectivity curve when a station is closely tuned in, a thermionic tube having a grid and controlling said power actuated tuning means, and means including rectifying means for applying a control voltage dependent on the difference between the single peaked and double peaked voltages to the grid of said thermionic tube to stop said tuning means when a station is closely tuned in thereby.

11. In a radio receiver having variable tuning means, in combination, power means driving said tuning means, relay means for stopping and starting said power and tuning means, an electron tube having a plate circuit connected to said relay means and a grid for controlling said plate current for operating said relay means to stop said tuning means, tuned coupling means deriving from said receiver a first control voltage having a selectivity curve with two peaks and a depression therebetween, tuned coupling means deriving from said receiver a second control voltage having a selectivity curve with a single peak coinciding in frequency with said depression and exceeding said first control voltage when a carrier signal is closely tuned, means including rectifying means for applying a control voltage depending upon the difference between said first and second control voltages to said grid when said carrier signal is closely tuned to operate said relay means and stop said tuning means closely on said carrier signal, means including a circuit controlled by said relay upon operation thereof to stop said tuning means for applying additional grid bias voltage to said grid to prevent a decrease in carrier signal strength from operating said relay means, and means actuatable by an operator for operating said relay means to restart said power and tuning means.

12. In a radio receiver having a variable tuning element, in combination, power means for driving said tuning element, relay means adapted when energized to stop said power means and tuning element, an ionizable gas tube having a plate circuit connected to said relay means and a

control grid, means connected to said grid to supply it with a control voltage from the receiver for ionizing said gas tube and energizing said relay means when a carrier signal is closely tuned in, and a source of direct current connected to the plate circuit of said tube for maintaining said tube ionized and said relay means energized.

13. In a radio receiver having variable tuning means, in combination, power means driving said tuning means, relay means for stopping and starting said power and tuning means, an electron tube having a plate circuit connected to said relay means and a grid controlling the plate current for operating said relay means to stop said tuning means, tuned coupling means deriving from said receiver a first control voltage having a selectivity curve with two peaks and a depression therebetween, tuned coupling means deriving from said receiver a second control voltage having a selectivity curve with a single peak coinciding in frequency with said depression and exceeding said first control voltage when a carrier signal is closely tuned, means including rectifying means for applying a voltage depending upon the difference between said first and second control voltages to said grid when said carrier signal is closely tuned to operate said relay means and stop said tuning means closely on said carrier signal, and means actuatable by an operator for operating said relay means to restart said power and tuning means.

14. In a superheterodyne radio receiver having an intermediate frequency section and variable tuning means, in combination, power means driving said tuning means, relay means for stopping and starting said power means, an electron tube having a plate circuit connected to said relay means and a grid controlling the plate current for operating said relay means to stop said tuning means, means coupled to said intermediate frequency section and tuned to intermediate frequency for deriving from said receiver a first control voltage having a selectivity curve with two peaks and a depression therebetween, means coupled to said intermediate frequency section and tuned to intermediate frequency for deriving from said receiver a second control voltage having a selectivity curve with a single peak coinciding in frequency with said depression and exceeding said first control voltage when a carrier signal is closely tuned, means including rectifying means for applying a voltage depending upon the difference between said first and second control voltages to said grid when said carrier signal is closely tuned to operate said relay means and stop said tuning means closely on said carrier signal, and means actuatable by an operator for operating said relay means to restart said power and tuning means.

15. In a superheterodyne radio receiver having an intermediate frequency section and variable tuning means, in combination, power means driving said tuning means, relay means for stopping and starting said power means, said relay means being energizable to stop and deenergizable to start said power means, an ionizable gas tube having a plate circuit connected to said relay means, said tube being non-conductive during operation of said tuning means and having a control grid adapted to be supplied with a control voltage to render said tube conductive to energize said relay means, means coupled to said intermediate frequency section and tuned to intermediate frequency for deriving from said receiver a first control voltage having a selectivity

curve with two peaks and a depression therebetween, means coupled to said intermediate frequency section and tuned to intermediate frequency for deriving from said receiver a second control voltage having a selectivity curve with a single peak coinciding in frequency with said depression and exceeding said first control voltage when a carrier signal is closely tuned, means including rectifying means for applying a control voltage depending upon the difference between said first and second control voltages to said grid when said carrier signal is closely tuned to render said tube conductive and energize said relay means to stop said tuning means closely on said carrier signal, and means actuatable by an operator for deionizing said tube and deenergizing said relay means to restart said power and tuning means.

16. In a superheterodyne receiver having an intermediate frequency section, an amplifying tube preceding said section, and variable tuning means, in combination, power means driving said tuning means, relay means for stopping and starting said power means, an electron tube having a plate circuit connected to said relay means and a grid controlling the plate current for operating said relay means to stop said tuning means, means coupled to said intermediate frequency section and tuned to intermediate frequency for deriving from said receiver a first control voltage having a selectivity curve with two peaks and a depression therebetween, means coupled to said intermediate frequency section and tuned to intermediate frequency for deriving from said receiver a second control voltage having a selectivity curve with a single peak coinciding in frequency with said depression and exceeding said first control voltage when a carrier signal is closely tuned, means including rectifying means for applying a control voltage depending upon the difference between said first and second control voltages to said grid when said carrier signal is closely tuned to operate said relay means and stop said tuning means closely on said carrier signal, means controlling the grid bias of said amplifying tube for preventing operation of said relay in response to carrier signals below intensities determined by said grid bias controlling means, and means actuatable by an operator for operating said relay means to restart said power and tuning means.

17. In a radio receiver having a variable tuning element, in combination, power means for driving said tuning element, relay means controlling said power means and tuning element, said relay means being operable when deenergized to render said power means effective to drive the tuning element and when energized to stop said power means and tuning element, an ionizable gas tube having a cathode, plate and control grid, a source of direct current voltage, said source being connected across the plate and cathode of said tube in series with said relay means, means including a grid bias resistor connected between said cathode and the negative side of said voltage source and a second resistor connected between the positive side of said voltage source and said cathode for biasing said control grid to deionize said tube when said relay means is deenergized, and means connected to said grid to supply it with a control voltage from the receiver for ionizing said tube and energizing said relay when a carrier signal is closely tuned in.

18. In a radio receiver having a variable tuning

element, in combination, power means for driving said tuning element, relay means controlling said power means and tuning element, said relay means being operable when deenergized to render said power means effective to drive the tuning element and when energized to stop said power means and tuning element, an ionizable gas tube having a cathode, plate and control grid, a source of direct current voltage, said source being connected across the plate and cathode of said tube in series with said relay means, means including a grid bias resistor connected between said cathode and the negative side of said voltage source and a second resistor connected between the positive side of said voltage source and said cathode for biasing said control grid to deionize said tube when said relay means is deenergized, means connected to said grid to supply it with a control voltage from the receiver for ionizing said tube and energizing said relay when a carrier signal is closely tuned in, and normally closed switch means in the plate-cathode circuit of said tube for deionizing said tube and de-energizing said relay means.

19. In a radio receiver having variable tuning means operable between predetermined limits, in combination, a reversible electric motor for driving said tuning means in opposite directions, a source of power for said motor, means including a relay and switch means operated thereby controlling the connections of the motor to said power source for starting and stopping said power means, means including limit switch mechanism actuated by said tuning means and controlling the connections of said motor to said power source for automatically reversing the motor at the limits of movement of said tuning

means, means including an electron tube having its plate circuit connected to said relay for operating said relay to effect disconnection of said motor from said power source when a carrier signal is tuned in, and switch means operable by an operator controlling said relay and connections of the motor to said power source for reversing said motor when said tuning means is between the limits of its movement.

20. In a radio receiver having variable tuning means, operable between predetermined limits, in combination, a reversible electric motor for driving said tuning means in opposite directions, a source of power for said motor, means including a relay and switch means operated thereby controlling the connections of the motor to said power source for starting and stopping said power means, means including a reversing switch controlling the connections of said motor to said power source, a second relay controlling said reversing switch and limit switch mechanism actuated by said tuning means adapted to energize said relay at one limit and to deenergize said relay at the other limit of movement of said tuning means for automatically reversing said motor, means including an electron tube having its plate circuit connected to said first relay for operating said relay to effect disconnection of said motor from said power source when a carrier signal is tuned in, and switch means operable by an operator for energizing said second relay independently of said limit switch mechanism for initiating operation of said motor in a direction opposite to that determined by said limit switch mechanism.

EDWARD F. ANDREWS.
